(57) **CLAIM**

The ornamental design for a eyebrow trimming scissors with comb as shown and described.

DESCRIPTION

FIG. 1 is a perspective view of a eyebrow trimming scissors with comb showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and

FIG. 8 is a bottom plan view thereof; and,

FIG. 9 is an enlarged view of a portion of the eyebrow trimming scissors with comb shown within the area designated as 9 in FIG. 6

The evenly spaced broken lines depict portions of the eyebrow trimming scissors with comb and form no part of the claimed design. The dot-dash broken lines encircling portions of the eyebrow trimming scissors with comb in FIG. 6 and illustrated in the enlarged view in FIG. 9 form no part of the claimed design.
